UNITED STATES PATENT OFFICE.

HENRY L. MYERS, OF PHILADELPHIA, PENNSYLVANIA, AND JOHN W. ROGERS, OF CAMDEN, NEW JERSEY.

GARMENT AND CARRYING DEVICE ATTACHED THERETO.

SPECIFICATION forming part of Letters Patent No. 322,844, dated July 21, 1885.

Application filed February 6, 1884. (No model.)

To all whom it may concern:

Be it known that we, HENRY L. MYERS, a citizen of the United States, residing in the city and county of Philadelphia, State of Pennsylvania, and JOHN W. ROGERS, a citizen of the United States, residing in the city and county of Camden, State of New Jersey, have invented a new and useful Improvement in Garments and Carrying Devices Attached Thereto, which improvement is fully set forth in the following specification and accompanying drawings, in which—

Figure 1 is a view of the inside of a coat embodying our invention. Fig. 2 is a view of the coat bundled, showing the carrying device or grip in operative position. Fig. 3 is a view on a reduced scale, showing the steps in the operation of forming the coat into a bundle and locating the carrying device.

Similar letters of reference indicate corresponding parts in the several figures.

Our invention consists of a novel bundling and carrying device for a garment, as will be hereinafter fully set forth.

Referring to the drawings, A represents a coat of the order of a duster, and B one of the pockets thereof, depending as usual on the inside.

C represents a flap attached to the bottom of the pocket, and D D represent flaps attached to the sides of said pocket near the bottom, it being evident that the flaps C D may be integral portions of the pocket.

E represents a strap-handle or grip, which is sewed, as at a, to the bottom of the pocket on the side adjacent to the skirt of the coat, and has button-holes b formed in its ends. To the pocket near the upper end on the side adjacent to the skirt are secured buttons c', so disposed that said buttons c' may pass through button-holes c" in the flap C. The ends of the handle or grip E may be connected with said buttons c', and the ends of the flaps C D may be connected with the button c, as will be hereinafter more fully stated.

The coat is folded in the longitudinal direction—in the present case in three widths along the dotted lines d, and nearly in half along the dotted line e—the halves then being placed together, the pocket with attachments being left at one end thereof, as shown in Fig. 3. The

folds are then formed into a roll, the rolling being continued over the pocket, the pocket coiling around the roll, and is thus on the exterior. The flaps D are then turned over on the roll, thus inclosing the ends thereof, and the flap C turned over the flaps D, the flaps being buttoned, as at c, whereby they are prevented from opening or separating. The handle or grip E is now in position at what is the top of the bundle, and its ends are attached to the button c', whereby the garment may be readily carried by said handle or grip, as shown in Fig. 2, it being seen that the bundle is compact and presents the appearance of a bag or satchel, and the handle is securely attached in position, as it is stitched to the flap C and has its ends fastened to the buttons c', which latter are passed through the button-holes c", and likewise connect the flap C with the top of the pocket as rolled, and also connect the outer folds of the roll. When the flaps are unbuttoned, the coat may be unrolled, so as to perform its usual service, and the flaps may be pinned or buttoned together or remain opened out and pinned or buttoned to the skirt of the coat.

It is evident that the invention is applicable to other coats than dusters—such as waterproofs or gossamers and overcoats generally, as well as to other garments.

Where a pocket does not exist in a coat, a piece of fabric may be secured to the coat, the flaps, &c., being attached thereto, the effect being the same as that previously stated.

Having thus described our invention, what we claim as new, and desire to secure by Letters Patent, is—

1. A pocket of a garment provided with a flap connected with one end thereof and flaps connected with the sides of the same, substantially as and for the purpose set forth.

2. A pocket of a garment having a flap, buttoning devices, and a handle-strap, said flap and strap being at the bottom of the pocket, whereby, when the garment is formed into a roll, the pocket and flap are coiled around the same and the flap buttoned to the pocket, the handle-strap being presented for carrying purposes, substantially as and for the purpose set forth.

3. A pocket of a garment, in combination

with flaps attached to the sides thereof and a handle-strap, whereby the garment may be rolled within the pocket, the sides of the roll covered by said flaps, and the bundle as formed carried by said strap, substantially as and for the purpose set forth.

4. A pocket of a garment, in combination with a flap attached thereto at one end, flaps attached to the sides of said pocket, and a handle-strap attached to said end flap, substantially as and for the purpose set forth.

5. A garment having a pocket with buttons

c c', a flap with a button-hole attached to the end of the pocket, flaps with button-holes attached to the sides of the pocket, and a handle-strap attached to the end flap with button-holes *b* in its ends, substantially as and for the purpose set forth. 15
